UNITED STATES PATENT OFFICE.

FRED C. LAMP, OF CLEVELAND, OHIO.

TELESCOPIC SAFETY-ZONE STANDARD.

Application filed March 25, 1925. Serial No. 18,191.

To all whom it may concern:

Be it known that I, FRED C. LAMP, a citizen of the United States, residing at Cleveland, in the county of Cuyahoga and State 5 of Ohio, have invented a new and useful Telescopic Safety-Zone Standard, of which the following is a specification.

The object of my invention is to provide a telescopic traffic signal which may be used 10 to mark off a safety zone device at the intersection of streets for the protection of pedestrians and also to mark off spaces in the street to protect people getting on or off street cars and in which space motor vehicles 15 are not allowed to enter. It is also an object of my invention to provide novel means for permitting of conveniently telescoping the signal when its use is not required. These and other objects of my invention are attained by the device illustrated 20 in the accompanying drawings, in which—

Figure 1 is a view partly in section and partly in side elevation of my invention with the inner standard in its elevated position;

Fig. 2 is a view partly in section and partly in elevation of my invention with the inner standard partially lowered;

Fig. 3 is a vertical section with the inner 30 standard in its lowered position;

Fig. 4 is a top plan view of my device;

Fig. 5 is a horizontal section on line 5—5 of Fig. 2;

Fig. 6 is a horizontal section on line 6—6 of Fig. 2; and

Fig. 7 is a detail sectional view of the resilient electrical contact mechanism.

Like numerals indicate like parts in each of the several views.

Referring to the accompanying drawings, 40 I provide a steel tube or pipe 1, which pipe is sunk in the street so its uppermost edge is level with the surface of the street or pavement. Telescopically mounted in outer 45 pipe 1 is an inner pipe or standard 7 which is provided with a metal cap 9 which when the inner standard 7 is lowered extends over the top of the outer standard and rests on the top of the pavement so that vehicles can 50 drive over it without damage to the vehicles or to the standard. Cap 9 has a suitable ring or handle 10, as shown, for pulling the standard up. A felt packing 6, and stuffing box collars 5 which are screwed into the 55 interiorly threaded upper end of outer pipe 1, form a water-tight closure for the

top of the outer standard. The outer pipe is provided with one or more annular grooves, such as the grooves 2 and 3 illustrated in the drawings, while the inner pipe 60 or standard 7 is provided with one or more resilient groove-engaging devices for releasably engaging the correspondingly arranged groove or grooves in the outer pipe when the inner pipe is raised in its elevated 65 operative position. The form of resilient groove engaging device which I prefer consists of spaced rings, discs or plugs 12 with a central core or block 17 and with balls 14 which are mounted in the apertures 13 and 70 normally pressed outwardly by springs 15.

Near the upper end of inner pipe or standard 7 I provide windows 8 through which the warning signal lamp 25 may throw its rays. Lamp 25 is connected by 75 wires 26 with the contact rings 18 which are mounted on insulating rings 19 encircling the inner standard near the lower end of same, as shown in Fig. 3. When the standard is raised the contact rings 18 move 80 into physical and electrical contact with the spaced slidably mounted contact members 20, the rear portions of which are engaged by springs 21, connected by screws 25 to the wires 22 leading to a suitable source of current. All of these elements are mounted in insulating material as illustrated in detail in Fig. 7 and the wires 22 are preferably 85 inclosed in a suitable conduit 23. Referring to Fig. 3 of the drawings, the device is 90 shown in its lowered inoperative position in which position electric circuit to lamp 25 is broken. In Fig. 2 the device is shown in a partially raised position, handle 10 being used to pull the inner standard up to an 95 operative position, which latter position is illustrated in Fig. 1. In that position the resiliently pressed balls 14 seat in the grooves 2 and 3 and releasably lock the standard in its elevated operative position. At the same time, the electrical contact rings 18 are in a position to contact with the resiliently mounted contact members 20 and complete the electric circuit to the lamp 8 which is thereby automatically illuminated and which by reason of the windows 8, which may if desired, be provided with stained glass to serve as a warning to motorists to keep off of the safety zone. The device is one that does not have to be moved back and forth 105 as do the safety zone signals now in general use but is a permanent fixture in the street.

and one that is conveniently operated and which provides an efficient warning and affords a large degree of protection to the innocent pedestrian against the encroachment of reckless drivers. The pipes 7 and 1 can be made of any suitable size or height desired and of any suitable material. By providing a plurality of grooves 2 and 3 and because of the locking device shown, it is possible to move the standard to a position in which the uppermost locking device will seat in the groove 2, as shown in Fig. 2, in which position the standard will be locked in a warning position in day use but the electric circuit will not be completed and the red lamp 25 will not be burning. When it is desired to have the red lamp burning the device must be elevated still further so that the resilient locking means will engage both the grooves 2 and 3 in which position the contact rings 19 will contact with the resilient contact members 20 and the lamp will be lighted.

What I claim is:

- 25 1. An outer pipe embedded in the ground and having its upper edge flush with the surface of the street, a standard telescopically mounted in the outer pipe, a sealing device for tightly sealing the space between the top of the outer pipe and the outer wall of the inner standard, means on the inner standard for releasably locking it in its elevated position, and a cap on the top of the outer standard, said cap having a handle for raising the standard manually, said handle normally lying in a plane below or level with the top surface of the cap.
- 30 2. In a telescopic traffic signal, the combination of an outer pipe embedded in the earth and having its upper edge flush with the street, a standard telescopically mounted in the pipe, resilient means for releasably locking the inner standard in an elevated position, water-tight closure means closing the space between the top of the outer pipe

and the standard, a signal lamp in the standard, contact rings mounted on the lower portion of the inner standard, wires leading from the lamp to said contact rings, and a resilient contact element with which 50 said contact rings are adapted to form a releasable electric contact.

3. In combination with the apparatus described in claim 2, a cap mounted on the standard and of sufficient diameter to seat 55 over the upper surface of the outer pipe when the telescopic standard is lowered, and a handle member mounted on said cap.

4. In a telescopic traffic signal, the combination of an outer pipe embedded in the ground and having a plurality of spaced 60 grooves, a telescopic standard mounted in said outer pipe and carrying an electric lamp in its upper end, spaced electric contact rings mounted on the outer wall of said 65 standard, a plurality of resilient locking devices spaced apart and mounted on the lower end of the telescopic standard, resilient electric contact elements with which the electric contact rings will contact when the standard 70 is raised to a position in which the plurality of resilient locking devices engage in the plurality of grooves in the outer pipe and in which the electric circuit will not be completed when the upper resilient locking device 75 only engages in a groove in the outer pipe, whereby the telescopic standard may be locked in either of two operative positions, in one of which a signal lamp is lighted and in the other of which it is not lighted by 80 failure to complete the electric circuit to it.

5. In combination with the apparatus described in claim 4, a metal cap affixed to the top of the telescopic standard and of sufficient diameter to seat over the upper edge 85 of the outer pipe when the device is in lowered position to permit vehicles to pass over same readily.

FRED. C. LAMP.
